UNITED STATES PATENT OFFICE.

HENRY M. MILLER, OF FOSTER, WEST VIRGINIA, ASSIGNOR OF ONE-HALF TO JOEL O. STOLLINGS AND CHARLES W. LEFTWICH, OF MADISON, WEST VIRGINIA.

FIGURE TOY.

1,129,888.

Specification of Letters Patent.

Patented Mar. 2, 1915.

Application filed March 18, 1914. Serial No. 825,623.

To all whom it may concern:

Be it known that I, HENRY M. MILLER, a citizen of the United States, residing at Foster, in the county of Boone, State of West Virginia, have invented certain new and useful Improvements in Figure Toys; and I do hereby declare the following to be a full, clear, and exact description of the invention, such as will enable others skilled in the art to which it appertains to make and use the same.

The present invention is directed to improvements in figure toys, and more particularly to toys which simulate a person dancing.

The invention has for its object to provide a toy which can be readily applied to the motor casing of a graphophone and will be actuated by the turn table or platform.

20 A further object of the invention is to provide a dancing figure which will be set in motion during the rotation of the turn table or platform of the graphophone so that during the playing of the graphophone 25 the antics of the figure will afford amusement.

With these and other objects in view, this invention resides in the novel features of construction, formation, combination and arrangement of parts to be hereinafter more fully described, claimed and illustrated in the accompanying drawing, in which:—

Figure 1 is a side elevation of a graphophone showing the device attached thereto. 35 Fig. 2 is a sectional view on line 2—2 of Fig. 1. Fig. 3 is an enlarged fragmentary view of the device, the parts thereof being in section. Fig. 4 is a fragmentary bottom plan view of the turn table.

40 Referring to the drawing, the numeral 1 designates the casing of a graphophone of a well known construction which contains a motor for rotating the turn table 2 for supporting the disk records.

45 Having its lower end fixed to the top of the casing 1 is an arm 3, preferably formed from wire and has its upper end formed with a hook 4 for engagement by the other end of the cord 5 which suspends the figure 6, the arms and legs of which are jointed so that when movement is imparted to the figure the same will simulate dancing.

To agitate the figure a flat spring arm

7 is provided and has one end fixed to the top of the casing 1 and is provided with an upwardly bowed portion 8 intermediate its ends, the purpose of which will appear later. Supported by the outer end of the arm 7 is a platform 9 which is so disposed that the same will be directly under the figure so that the feet thereof rest thereupon. The arm 7 engages the loop 10 which is supported by the top of the casing 1, said loop serving to retain the arm in a position so that the platform 9 will be subjected to sharp vibrations.

The underface of the turn table 2 is provided with lugs 11, said lugs being detachably secured thereto and adapted to engage the bowed portion 8, of the arm 7 during the rotation of the table, thus imparting vibration to the arm and platform to actuate the figure. I do not however wish to be limited to this particular form of lug, as for instance, the turn tables of different makes of machines are frequently provided with annular flanges, and when applying the invention to such machines the construction of the lugs will necessarily need to be somewhat modified.

From the foregoing description it will be seen that during the rotation of the turn table that vibratory motion will be imparted to the arm, thus actuating the figure to simulate a person dancing. If desired, a pair of figures may be employed, which is readily accomplished by slightly changing the formation of the arm 3.

What is claimed is:—

The combination with a casing having a motor driven turn table, of lugs carried by the turn table, a resilient arm having one end fixed to the casing and its other end provided with a platform, said arm having a central upwardly bowed portion, a figure suspended adjacent the casing, movement being imparted to the figure during the rotation of the turn table and when the lugs carried thereby contact with the bowed portion.

In testimony whereof, I affix my signature, in presence of two witnesses.

HENRY M. MILLER.
